HANDLE AND OPERATING LEVER ASSEMBLY
FOR FLUSHING TANKSDavid E. Gulick, Kittanning, Pa., assignor to
Eljer Co., Ford City, Pa.

Application July 20, 1948, Serial No. 39,617

6 Claims. (Cl. 4—67)

1

This invention relates to a handle and operating lever assembly for flushing tanks of any character, as for instance, flushing tanks employed in connection with toilets.

The object of the invention is to provide for mounting the bearing member of the assembly in a wall of the flushing tank in such a manner as to prevent looseness of the bearing member in the opening through the tank wall.

It is a common practice to provide tank walls with a rectangular opening to accommodate the fixed or stationary bearing member for the rocking shank or spindle of the handle and lever assembly. Inasmuch as such openings necessarily vary somewhat in proportions and shape, it is necessary to provide for holding the bearing member against rotative looseness in the opening. Heretofore this has been done by fixed or rigid means on the bearing member, but this has been unsatisfactory for the reason that the fixed means does not accommodate itself to variations in the size or shape of the opening through the tank wall.

In carrying out the present invention, the bearing member is provided with means which will accommodate itself to the size and shape of the opening in the tank, when the bearing is being fitted in place in said opening, and thereby ensure a snug engagement with walls of the opening such that the bearing will be effectively held against rotative looseness.

With these and other objects in view, the present invention consists in the combination and arrangement of parts as will be hereinafter more fully described, illustrated in the accompanying drawings and pointed out in the appended claims, it, of course, being understood that changes in the form, proportion, size and minor details may be made, within the scope of the claims, without departing from the spirit or sacrificing any of the advantages of the invention.

In the drawings—

Figure 1 is a front elevation of a handle and operating lever assembly for flushing tanks embodying the features of the present invention.

Figure 2 is a plan sectional view taken through a wall of a flushing tank and showing the present assembly mounted in position in an opening through the wall of the tank.

Figure 3 is a detail sectional view on the line 3—3 of Figure 2.

Figure 4 is a detail sectional view on the line 4—4 of Figure 2.

Figure 5 is a fragmentary side elevation of the bearing member of the present invention look-

2

ing at a corner of a rectangular portion thereof. Figure 6 is a complete sectional view taken longitudinally through the mounting and showing the bearing in its normal condition clamped against the wall of the flushing tank.

Figure 7 is a detail elevation of the inner end of the shank or spindle of the handle member of the assembly prior to its assembly with the bearing member.

Figure 8 is a detail sectional view of the bearing member on the line 8—8 of Figure 9.

Figure 9 is a front elevation of the bearing member.

Figure 10 is a rear end view of the bearing member.

Figures 11 and 12 are detail fragmentary sectional views illustrating successive steps in the formation of a portion of the bearing member.

Figure 13 is a sectional view illustrating another method of forming the same portions of the bearing member.

Figure 14 is a view similar to Figure 2 showing another embodiment of the present invention.

Figure 15 is a fragmentary sectional view of the locking means for the bearing as illustrated in Figure 14.

Figure 16 is an elevation of one end of the locking means employed in Figure 14.

Figure 17 is an elevation of the opposite end of the locking means shown in Figure 14.

Figure 18 is a detail view of the bearing member employed in Figure 14 and showing the longitudinal groove or keyway therein.

Figure 19 is an enlarged detail sectional view taken on the line 19—19 of Figure 14.

Figure 20 is a side elevation of the bearing member showing a modification therein.

Figure 21 is a rear end view of Figure 20.

Figure 22 is similar to Figure 20 showing another modification.

Figure 23 is a rear end view of Figure 22.

Referring at first to Figures 1 to 7, inclusive, it will be seen that a front wall of the flushing tank has been indicated in section by the reference numeral 1, through which wall there is a rectangular opening 2 as is the common practice in devices of the present type. The handle member of the assembly is designated 3 and may be of any preferred form, while the lever member is

designated 4 and is intended to be provided with a depending link connected at its lower end to a ball valve, not shown, but common and well understood in devices of the present type.

As usual, the handle 3 is provided with a shank 5 or spindle 5, the base of which is surrounded by a

circumferential flange constituting a cup or casing which is open at that end which is remote from the handle. The lever 4 has a terminal crank member 7 which may be connected to the inner end of the shank or spindle 5 in any preferred manner. In the accompanying drawings, the crank portion 7 is received within a terminal socket 8 in the shank and has a tight fit therein against independent rotation whereby operation of the handle 3 will turn the shank 5 and swing the lever 4 on the fulcrum provided by the shank 5.

The mounting for the shank 5 is an open-ended tubular bearing member 9 which extends through the opening 2 in the wall of the flushing tank and houses the shank 5 in the bore of the tube. Endwise separation of the shank 5 from the bearing is prevented by means of an annular shoulder 10 on the base of the shank and lips or projections 11 on the rear end of the shank, which projections are normally in the position shown in Figure 7 extending longitudinally of the shank and are bent outwardly across the rear end of the bearing 9, as shown in Figure 6, to prevent endwise separation of the parts in one direction.

The shank or spindle 5 has a limited rotation within the tubular bearing member 9 brought about by means of a stop projection 12 projecting from the outer face of the head or flange 13 provided upon the outer end of the bearing member 9. The stop member 12 is disposed between co-operating stop projections 14 provided upon the handle 3 and within the cup or casing portion 6 thereof as well illustrated in Figures 4 and 6 of the drawings.

The bearing 9 is held to the tank wall 1 by means of a nut 15 provided upon the screw-threaded exterior portion of the bearing at the inner side of the tank and the annular head or flange 13 carried by the front end of the bearing member. Also, the portion of the bearing member 9 adjacent the head or flange 13, as indicated at 16 is rectangular in shape as best shown in Figure 3 of the drawings and is intended to fit within the rectangular opening 2 in the tank wall 1. As heretofore explained, it is practically impossible to make the rectangular openings in a number of tanks absolutely accurate so as to have the rectangular portion 16 of the bearing fit snugly the walls of the opening in any one tank and thereby prevent any rotative looseness of the bearing. According to the present invention, the rectangular portion 16 is made of a size and proportions to approximately fit the opening in the tank wall, and then wings or projections 17 are punched out at the corners of the rectangular portion so that the four wings will spread and engage the corner walls of the opening 2 when the bearing member is initially thrust through the opening 2. Thereafter, upon manipulation of the nut 15 to draw the bearing member endwise through the opening 2, the wings 17 will be crowded into the corners of the opening 2 when the head or flange 13 of the bearing has been drawn tightly against the outer face of the tank wall 1. It will here be explained that the bearing member 9 is sufficiently soft to enable the punching out of the wings 17, and to enable the crowding of such wings into the corners of the opening 2 when the bearing is forced endwise through the opening by the manipulation of the nut 15. It will now be understood that the walls of the rectangular portion 16 of the bearing member need not necessarily have

a contact fit with the walls of the opening 2 in the tank wall because the wedging of the relatively soft wings or projections 17 into the angles at the corners of the rectangular opening in the tank wall will effectively lock the bearing to the walls of the opening 2 and thus lock the bearing against any rotating looseness within the opening in the tank wall.

In order to form the wings or projections 17 at the corners of the rectangular portion 16 of the bearing member, the head or flange 13 of the bearing is provided with four openings 18 extending entirely through the flange and located opposite the respective corners of the rectangular portion 16 of the bearing as well shown in Figure 9. These openings are intended to accommodate tools, such as indicated in dotted lines in Figure 12, whereby the wings 17 may be punched from the corners of the rectangular portion 16 of the bearing.

Another way of forming the wings 17 is by casting as illustrated in Figure 13, wherein 19 and 20 are mold members. The mold member 19 is provided with a cavity of a shape to give 25 to the bearing the form shown in Figures 8 and 12, while the mold member 20 is provided with four bosses, two of which have been shown at 21, each boss having a wedge-shaped member 22 to form one of the wings 17 during the casting operation.

Instead of having the deformable wings 17, the bearing member may, as in Figures 19 and 20, be provided with deformable members 23 on the back of the flange 13 and/or on the periphery 35 of the rectangular portion 16 so that when the nut 15 is manipulated to draw the bearing through the opening in the tank wall, the deformable projections 23 will be drawn into and crowded against the walls of said opening in a 40 manner to lock the bearing member against rotation in either direction on its axis. In Figures 21 and 22, a series of relatively thin deformable projections 24 are provided at the back of the flange 13 and on the peripheral faces 45 of the square portion 16 of the bearing.

Instead of locking the bearing 9 at the outer or forward end of the opening 2 in the tank wall, as shown in Figure 2, the locking arrangement may be provided at the inner end of said opening 50 as shown in Figure 14, wherein the wings or projections 17 are omitted from the square portion 16 of the bearing and are provided on a washer 25 embracing the inner end portion of the bearing 9 and interposed between the nut 15 and the inner or back face of the wall 1 of the tank.

This washer is provided with an internal projection or key 26 designed to engage a longitudinal groove or key way 27 formed in the screw-threaded portion of the bearing, see Figure 18, 60 for the purpose of preventing rotation of the washer on the bearing. The washer has a rectangular portion 28 provided with the deformable wings 29 at the corners thereof, the flange portion of the washer being provided with openings 30, like the openings 18 of Figures 8 to 12, inclusive, to receive a tool for punching out each of the wings. With such a washer provided upon the bearing 9 and interposed between the nut 15 and the rear face of the tank wall 1, by manipulation 65 of the nut 15 the washer may move longitudinally of the bearing until its square portion and the wings have been forced into the rear open end portion of the opening 2 and the wings forced or crowded into the corners of the rectangular opening so as to lock the washer and the bearing 70

against rotation or even rotatable looseness within the opening 2.

The manner of locking the bearing against rotatable looseness as shown in Figure 2 and as shown in Figure 14, is identical in that in each instance the deformable wing or projections are forced or crowded into the angles of the opening 2 in such a manner as to hold the bearing against rotatable looseness. In Figure 2 the wings 17 cooperate with the walls of the outer or forward end of the opening 2, while in Figure 14 the deformable wings 29 cooperate with the inner or rear end of the opening 2.

It will be noted that in each form of the invention the bearing member is provided with deformable wings or projections, 17 in Figures 2, 3 and 5; and 29 in Figures 14, 15, 16, 17 and 19. In Figures 2 and 3, the projections 17 are integral with the bearing member, while in Figures 14, 15, 16 and 19, the projections 29 are directly on the washer 25 and, therefore, are on or carried by the bearing member.

It will, of course, be understood that the parts as shown in Figures 2, 14 and 15 show the wings before they have been crowded into the angles of the opening 2 and are in position to be engaged with the walls of the opening by manipulation of the nut 15. Figures 3, 6 and 19 show the several wings crowded into the angles at the four corners of the rectangular opening 2 in the wall of the tank.

While the bearing member has been shown as provided with a rectangular portion and the tank has been shown as provided with a rectangular opening to receive the rectangular portion of the bearing, it is not the rectangular or other non-circular shape that is relied upon to prevent rotative looseness of the bearing member in the opening. Any shape of opening and cross sectional shape of the bearing member may be employed for the reason that it is the wedging or frictional engagement of the wings or projections against the walls of the opening that is relied upon to prevent rotative looseness of the bearing within the opening.

In this connection (see Figures 3 and 14) the space between the rectangular portion 16 of the bearing member and the walls of the opening 2 in the wall of the tank has been shown as exaggerated and emphasis is placed on the fact that it is the deformable wings or projections that are mainly relied upon to prevent rotative looseness of the bearing within the opening. In Figure 19 the same exaggeration has been shown between the periphery of the washer 25 and the walls of the opening in the tank.

Having thus described my invention, what I claim is:

1. A handle and operating lever assembly for flushing tanks, comprising an open-ended tubular bearing member to extend through an opening in the wall of a flushing tank, adapted to receive for rocking movement therein a shank for connecting said handle and operating lever, the bearing member having a head to lie against one face of a wall of a tank, a nut threaded on the other end of said bearing member for engagement against the opposite face of the said wall of the tank, and said bearing being provided with one or more integral slanted projections the outer ends pointed toward the head and being spaced therefrom, spaced clearance between the outer ends of the projections and the bearing, the projections extending outwardly beyond the periphery of the bearing member to such an extent

that said projections will be crowded in to conform to the opening in a flushing tank when the nut is turned to draw the bearing through the opening in the tank to clamp the said nut and head against opposite faces of a wall of a flushing tank and thereby hold the bearing member against rotary looseness within the opening in the tank wall.

2. A handle and operating lever assembly for flushing tanks, comprising an open-ended tubular bearing member having an external head or flange, said member being provided with a screw-threaded portion and also with outwardly slanted integral bendable lugs, the outward ends of the lugs being adjacent to but spaced from the flange and also spaced from the bearing, openings through the flange opposite the ends of the lugs, a shank rotatably mounted in the bearing member, a lever connected to one end of the shank, and a nut provided on the screw-threaded portion of the bearing member substantially as and for the purpose described.

3. A bearing for an oscillatory mounting of a handle and lever assembly for flushing tanks, comprising an open-ended tubular bearing member, externally threaded at one end, the other end of said member being provided with an annular flange and slanted integral bendable projections extending outwardly beyond the periphery of the bearing member to such an extent that they will be bent into non-rotatable engagement with walls of a non-round opening in a wall of a flushing tank when the bearing member is being assembled within said opening.

4. The combination with a wall of a flushing tank having a non-circular opening extending therethrough, an open-ended bearing member, externally screw-threaded at one end, extending through the opening and projecting at opposite ends thereof, the unthreaded end of the bearing having an external head or securing means to engage the outer face of said wall of the tank, a nut on the screw-threaded end portion of the bearing to clamp the shoulder or securing means against the wall of the tank, said bearing being provided with slantingly projecting wings or lugs joined to the bearing member inwardly longitudinally from the external head and pointed toward the head, the outward ends of the wings being spaced from the head and spaced from the bearing member and being disposed in registration with corners of the opening through the wall of the tank and forced into the angles of said opening under the influence of the nut.

5. A handle and co-acting lever for flushing tanks mounted in a bearing, said bearing having a threaded shank portion with a flanged head or stop means for positioning, a threaded lock nut on the shank, one or more integral slanted projecting lugs extending beyond the diameter of the bearing, a flange adjacent the outer ends of the lugs but having spaced relation thereto, openings through the flange opposite the outer ends of the lugs and so positioned as to give access for forming and adjusting the lugs, the outer ends of the projecting lugs having a spaced clearance at the back and being disposed between the head and the lock nut, and the outer ends of the lugs being displaceable by bending to conform to the hole in which the bearing is secured through the tightening of the lock nut to prevent rotation of the bearing in the hole.

6. A co-acting handle and lever assembly mounted in a bearing, the bearing having an

exteriorly threaded portion, an unthreaded portion, and a positioning means at one end, a lock nut on the threaded portion, integral slanted projecting lugs disposed between the positioning means and the lock nut on the unthreaded portion, the lugs having clearance at their back to permit relatively easy bending displacement by tightening of the lock nut, to conform to the hole in which placed, a flange of larger diameter than the bearing, adjacent to but spaced from the outer ends of the lugs and openings through the flange opposite the ends of the lugs to provide access to the lugs.

DAVID E. GULICK.
